To all whom it may concern:

Be it known that we, William J. Blazek, a citizen of the United States, residing at New Lexington, in the county of Perry and State of Ohio; Richard C. Evans, a citizen of the United States, residing at Lancaster, in the county of Fairfield and State of Ohio; and Rex C. Barkley, a citizen of the United States, residing at New Lexington, in the county of Perry and State of Ohio, have invented a new, original, and ornamental Design for an Automatic Grinding Machine or Similar Article, of which the following is a specification, reference being had to the accompanying drawing forming a part thereof.

Fig. 1 is a perspective view of an automatic grinding machine or similar article showing our new design;

Fig. 2 is a top plan view on a slightly smaller scale;

Fig. 3 is an end elevational view looking toward the right hand side of the machine; and

Fig. 4 is a rear side elevational view thereof.
The end of the machine opposite that shown in Fig. 3 is identical in appearance to that disclosed in Fig. 3. We claim:

The ornamental design for an automatic grinding machine or similar article, substantially as shown and described.
